UNITED STATES PATENT OFFICE.

JOSEPH A. ANGLADA, OF JENKINTOWN, PENNSYLVANIA, ASSIGNOR OF ONE-HALF TO
CHARLES S. AKLEY, OF NEW YORK, N. Y.

PNEUMATIC LIFTING JACK.

1,414,718.

Specification of Letters Patent.

Patented May 2, 1922.

Application filed July 14, 1919, Serial No. 310,658. Renewed October 21, 1921. Serial No. 509,390.

To all whom it may concern:

Be it known that I, JOSEPH A. ANGLADA, a citizen of the United States, and resident of Jenkintown, county of Montgomery, and 5 State of Pennsylvania, have invented certain new and useful Improvements in Pneumatic Lifting Jacks, of which the following, together with the accompanying drawings, is a specification.

10 My invention relates to pneumatically actuated lifting jacks and more particularly to light portable jacks such as may be used for lifting automobiles, and its object is to provide a device of this character of simple and 15 inexpensive construction and efficient in operation. Another object is to provide as a part of the device a handle by means of which the jack may be positioned. More specifically its object is to provide an extensible handle for this purpose. Another 20 object is to provide a simple arrangement for limiting the lifting movement of the jack. A still further object is to provide a simple arrangement for controlling the 25 movement of the jack by means of the positioning handle.

These and other objects of the invention will appear in the following specification, in which I will describe the invention, the 30 novel features of which will be set forth in appended claims.

Referring to the drawings, Figure 1 is a side elevation of a lifting jack which is made according to and embodies this invention.

35 Figure 2 is a front elevation of the same device.

Figure 3 is a plan view of the device shown in Figures 1 and 2.

Figure 4 is a sectional side of the device 40 with the positioning handle extended and with its valve opening position indicated by broken lines. The section in this figure is taken on the line 4—4 of Figure 3.

Figure 5 is a partial front sectional elevation.

Like characters of reference designate corresponding parts in all of the figures of the drawings.

10 is a cylinder closed at the bottom by a 50 base 11 and having a cover 12 at the top.

13 is a load receiving member which is connected with a piston 14 in the cylinder by a plunger 15 which passes through the cover. The piston preferably comprises a

downwardly faced cup washer 16, an upwardly faced flanged disk 17 above it and another upwardly faced flanged disk 18 within the washer, having a central hub into which a reduced threaded end of the plunger is screwed to hold the parts of the piston together. This construction is decidedly simple and strong and has the advantage of filling the lower end of the cylinder when it is in its lowermost position, so that but little air is required to give it its initial upward movement.

Air under pressure from any suitable source of pressure supply is admitted under the piston through a check valve 20 which is preferably an ordinary tire valve, and through a passage 21 in the base. This of course, causes an upward movement of the piston and the parts connected therewith, which movement will continue if enough air is supplied, until the piston has reached the 75 position indicated by dot and dash lines at 15^a in Figure 4.

In the wall of the cylinder 10 is an oil hole 19 by means of which the cylinder and piston may be lubricated. When the bottom of the 80 piston reaches and uncovers this hole, it serves as a discharge port for the compressed air in the cylinder and consequently arrests further upward movement of the piston.

22 is a discharge passage in base 11 closed 85 by a spring pressed valve 23 the upper end of which is designated by 24.

Directly above and at either side of this valve part 24 are ears 30 in which is pivoted the lower end of the lower section 31 of the 90 positioning handle. This handle may be made of a plurality of telescoping parts or sections 31, 32 and 33 so that it may be extended in length.

By means of this handle, connected as it 95 is near the base of the cylinder, the device may be placed where desired, for example, under a desired part of an automobile without the user having to stoop or reach under the machine.

Near its pivot, the handle section 31 is constructed to form a cam 34 which when the section is moved down into the position indicated by the dot and dash lines at 31^a in Figure 4, engages valve end 24 and depresses 105 valve 23 to open the outlet passage 22 to discharge. This causes the piston and the parts connected therewith to descend and of course

the rate and extent of its descent may be easily and conveniently controlled by simple movements of the handle.

The inventive thought upon which this application is based is broader than the particular mechanism shown and described as illustrative thereof and I intend no limitations other than those imposed by the appended claims.

10 What I claim is:

1. A lifting jack comprising a load receiving support, fluid actuated means for raising the support a control valve and a positioning handle movably connected with the jack and arranged to control the valve.
- 15 2. A lifting jack comprising a load receiving support, a pressure cylinder and a piston, means for introducing fluid into the cylinder, an outlet valve, and a positioning handle movably connected with the jack and arranged to control the outlet valve.
- 20 3. A lifting jack comprising a load receiving support, a pressure cylinder and a piston, means for introducing fluid into the cylinder, an outlet valve, and a handle pivotally connected with the jack near the lower part thereof and arranged to control the outlet valve.
- 25 4. A lifting jack comprising a load receiving support, a pressure cylinder and a piston, means for introducing fluid into the cylinder, an outlet valve, and a positioning handle pivotally connected with the jack near the lower part thereof and a cam on said handle arranged to engage and actuate the outlet valve.
- 30 5. A lifting jack comprising a load receiving support, a pressure cylinder and a piston,

means for introducing fluid into the cylinder, an outlet valve, and an extensible telescopic handle pivotally connected with the jack near the lower part thereof and a cam on said handle arranged to engage and actuate the outlet valve.

6. A lifting jack comprising a pressure cylinder and a piston therein, said piston comprising a downwardly faced cup washer and a disc having upwardly faced flanges arranged to fill the space within the washer, a piston rod connected with the inner flange of said disc, and means for introducing fluid under pressure into the cylinder, an outlet valve, and a positioning handle movably connected with the jack near the lower part thereof and arranged to control the outlet valve.

7. A lifting jack comprising a pressure cylinder and a piston therein, said piston comprising a downwardly faced cup washer and a disc having upwardly faced flanges arranged to fill the space within the washer, a piston rod connected with the inner flange of said disc, means for introducing fluid under pressure into the cylinder near one of its ends, the wall of said cylinder being constructed to form an orifice near the other end thereof and the piston being arranged to uncover said orifice when it reaches the upper end of its travel, an outlet valve, and a positioning handle movably connected with the jack near the lower part thereof and arranged to control the outlet valve.

In witness whereof, I have hereunto set my hand this 11th day of July, 1919.

JOSEPH A. ANGLADA.

Certificate of Correction.

It is hereby certified that the name of the assignee in Letters Patent No. 1,414,718, granted May 2, 1922, upon the application of Joseph A. Anglada, of Jenkintown, Pennsylvania, for an improvement in "Pneumatic Lifting Jacks," was erroneously written and printed as "Charles S. Akley," whereas said name should have been written and printed as *Charles S. Ackley*, as shown by the records of assignments in this office; and that the said Letters Patent should be read with this correction therein that the same may conform to the record of the case in the Patent Office.

Signed and sealed this 30th day of May, A. D., 1922.

[SEAL.]

KARL FENNING,

Acting Commissioner of Patents.
